COUPLING SYSTEM

Original application filed February 15, 1929, Serial No. 340,244, and in Canada January 2, 1930. Divided and this application filed November 25, 1930. Serial No. 498,026.

The present application is a division of application Serial No. 340,244, filed February 15, 1929.

This invention relates to radio coupling systems, particularly to transformers for use in coupling two successive vacuum tubes in a radio-frequency amplifier, and also in coupling an antenna system to such an amplifier, intended for the efficient reception of two or 10 more different frequency, or wavelength bands.

To this end the invention employs coupling transformers having a multiplicity of windings so related to each other that the several 15 primary coils operate as a single primary and the several secondary coils operate as a single secondary over one given frequency band, but that only certain of the primary and secondary coils operate as a single trans- 20 former over another given frequency band. A further feature of the invention is an im- proved frequency-amplification characteris- tic by reason of the provision of precalcu- lated reactions between the various coils.

25 In the past, three expedients have been most commonly employed for the reception of two or more widely differing frequency bands. The first is the use of as many separate re- ceivers or amplifiers as there are different 30 bands to be received. The second consists in employing a separate transformer especially designed for each frequency band; the various transformers having plug terminals which, when inserted in a suitable receptacle, 35 automatically establish the required electrical connections with the associated apparatus. The third expedient consists in permanently mounting as many physically separate trans- 40 formers as there are different frequency bands to be received, and shifting the connections of the transformers with the associated apparatus from one transformer to another by means of an appropriate multi- 45 point switching device.

The main objection to the first expedient is obviously that it is economically impracticable because of the attendant duplication of apparatus. The second and third expedients have, therefore, been proposed to ob- 50 viate the main objection to the first.

The second-named arrangement is electrically sound, but is clumsy and undesirable from the point of view of operation, be- 55 cause a shift from one frequency band to another necessitates the opening of the re- ceiver cabinet, the removal of one coil and the insertion of another. This operation is especially undesirable when the arrange- 60 ment is employed in a multi-stage amplifier because in such event it is necessary to change a number of transformers, which operation entails a considerable delay in tuning. Fur- 65 thermore, in this second arrangement, it fre- quently happens that the spare transform- 70 ers, i. e., those not for the moment employed within the receiver, become damaged or lost. Finally, the construction and duplication of such "plug-in" transformers is necessarily 75 expensive.

In the case of the third-mentioned expedient, the use of two or more entire sets of 75 transformers within the receiver is objec- tive- 80 tional because of the additional space re- quired and because of the increased cost. Furthermore, all the switching devices for 85 this apparatus thus far proposed are com- plicated, expensive, and subject to failure both electrically and mechanically. In the case of multi-stage amplifiers wherein large degrees of amplification are required, these complicated switching devices introduce both resistance and capacity losses which are detrimental to satisfactory operation of the 85 amplifier; and in addition, the exposed high- potential portions of the switch and its as- 90 sociated connections introduce detrimental capacitive couplings which are difficult, if not impossible, to eliminate and which, in

many cases, result in uncontrollable regeneration or oscillations.

The present invention contemplates not only the design of transformers of high efficiency whereby high amplification may be attained, but utilizes a more simple electrical and mechanical structure than has heretofore been employed in the reception of a plurality of frequency bands. An additional advantage of the invention results from the design of the transformers such that uniform, or substantially uniform, amplification is attained over one or more of the frequency bands, as desired. This invention overcomes all of the disadvantage of the prior arrangements, as pointed out, by providing a single transformer structure which may be permanently fitted in the receiver or amplifier, but which includes at least as many sets of windings as there are frequency bands to be received; the change from one frequency band to another being accomplished by short-circuiting or open-circuiting one or more of the unused coils in each transformer, such as the secondary coil for example, in which case the primary coils are always connected in circuit.

Before describing the invention with the aid of the accompanying drawings, it should be pointed out that this invention is not limited to use in tuned amplifier circuits but may be used with good success in untuned amplifiers. The invention is adapted to be used not only in combination with the common three-element tube, but also with the four-element tube, commonly known as the shield- or screen-grid tube (the particular type of tube employed having no special relation to this invention); it may likewise be employed as a coupling device in amplifiers whether or not they include neutralization, and for coupling the amplifier to an antenna as well as for coupling one vacuum tube with another. By "neutralization" is meant the neutralization of the capacitive coupling between two elements or electrodes of a vacuum tube together with the associated wiring, whereby the tendency towards the production of oscillations is reduced or eliminated.

Although Figure 1 of the drawings shows a typical physical embodiment of a coupling transformer in accordance with this invention, the description of the figures is so arranged that other figures relating to the application of the coupling transformer are first described in detail. This knowledge of the special applications of the coupling transformer facilitates understanding the significance of its structure.

Referring to the drawings:

Fig. 1 is a cross-sectional view of a coupling transformer arranged in accordance with this invention.

Fig. 1a and Fig. 1b show the amplification frequency curves of the transformer of Fig. 1 over two different frequency bands.

Fig. 2 shows a simple neutralized radio-frequency amplifier circuit including an intertube coupling system arranged in accordance with this invention. A third circuit is provided for neutralizing the effect of the grid-plate capacity of the tube.

Fig. 3 shows a radio-frequency amplifier, similar to that of Fig. 2 coupled by a special system, corresponding to the intertube coupling system hereinbefore described, to an antenna circuit.

Fig. 4 illustrates the approximate frequency characteristics of the antenna system of Fig. 3 over the particular two frequency bands considered.

The circuit of Fig. 5 is a modification of Figure 2 by which the amplification/frequency curve is made more nearly level.

Fig. 5a illustrates approximately the amplification/frequency curve obtained from the arrangement of Fig. 5.

The circuit diagram of Fig. 2 represents a tuned radio-frequency amplifier including two vacuum tubes A_1 and A_2 coupled by means of a system in accordance with this invention, including a coupling transformer comprising two primary windings L_1 and L_2 , two secondary windings L_3 and L_4 , and two neutralizing windings N_1 and N_2 . In effect, these six windings constitute two transformers, the first transformer L_1 , N_1 and L_3 being wound to comparatively small inductance to cover a high-frequency band; and the second transformer L_2 , N_2 and L_4 being wound to comparatively high inductance to cover a low-frequency band, altho, as is hereinafter pointed out, the "two transformers" may be designed to react upon each other in a definite, precalculated manner. For the convenience of the present discussion, the high-frequency tuning band may be considered as that between 500 and 1500 kilocycles, and the low-frequency tuning band as that between 150 and 300 kilocycles, these two bands being those at present employed for radio broadcasting in England. This particular example, however, is given only as a specific illustration of one embodiment of the invention; for obviously, other frequency bands may as well be accommodated. For instance, the invention may be used to advantage in radio receivers adapted to respond to the two broadcasting bands at present in effect in the United States, i. e., the band between 500 and 1500 kilocycles and that between 5000 and 7500 kilocycles.

When used for the reception of the lower radio-frequency band, the switch S_1 is opened, whereby the primary inductances L_1 and L_2 are in series in the plate circuit of vacuum tube A_1 , and the secondary windings L_3 and L_4 are in series in the input circuit of

vacuum tube A_2 . These two sets of windings then function like a single low radio-frequency transformer. Variable condenser C , connected to the extreme terminals of L_3 and L_4 , then operates to tune the coupling system over this band. When it is desired to receive over the high frequency band; the switch S_1 is closed, thus short-circuiting the low-frequency secondary L_4 , but leaving in circuit the high-frequency secondary L_3 with the variable tuning condenser C connected across its extremities. As is represented in the diagram, switch S_1 may be a simple single arm, single-contact switch, whose arm is always maintained at a fixed base potential. In all of the examples shown herein, this potential is that of the cathode or filament, usually known as "ground potential", and thus the switching device introduces practically no losses into the circuits. The entire coupling system is so designed that the single variable condenser C , having the proper capacity range, is equally useful for tuning, alternatively, over the low-frequency, or long-wavelength, band and the high-frequency, or short-wavelength, band, and over still other bands, if necessary. Reference to the figure will disclose that in shifting from the low-frequency band to the high-frequency band, both primary windings L_1 and L_2 remain connected.

When used for the reception of low frequencies, the two primary coils L_1 and L_2 , may be considered as a single primary winding associated with the secondaries L_3 and L_4 . When functioning as a high-frequency coupling system, the effective primary winding may be considered as only L_1 , and the secondary as only L_3 , because the electrical constants are chosen so that the primary L_2 has relatively small coupling with the secondary L_3 . This condition is brought about by a proper selection of the constants of the various coils, both individually and with respect to each other, in the following manner: The high-frequency primary L_1 may comprise a relatively small inductance closely coupled to the high-frequency secondary L_3 . The low-frequency primary L_2 connected in series with the high-frequency primary L_1 , comprises a larger inductance than L_1 , and is but loosely coupled to the high-frequency secondary L_3 .

When it is desired to receive signals within the low-frequency band, the short-circuiting switch S_1 is opened; thereby causing the entire secondary winding to be coupled to the entire primary winding, in which event necessary transfer of energy from the primary to the secondary is secured in most part by the relatively close coupling between the low-frequency primary L_2 and the low-frequency secondary L_4 . A slight increase in mutual inductance between the entire primary winding and the entire secondary wind-

ing is secured as a result of the coupling between the high-frequency primary L_1 and the entire secondary, but this is relatively small as compared with the mutual inductance between the low-frequency primary and secondary. 70

When it is desired to receive signals within the high-frequency band, the short-circuiting switch S_1 is closed, thereby short-circuiting the low-frequency secondary L_4 . The transfer of energy from primary to secondary is then effected through the combined couplings of L_1 and L_2 with the high-frequency secondary L_3 . Obviously, the major portion of the coupling for this band is between L_1 and L_3 . The physical position of winding L_2 with respect to L_3 is so adjusted that the electrical effect produced by the low-frequency primary L_2 upon the high-frequency secondary L_3 is relatively small when the low-frequency secondary L_4 is short-circuited. 85

Much attention must be paid to the proper choice of the electrical constants of the various coils and to the physical, and consequential electrical, relationship of these coils. In some cases, for example, the two frequency bands here under discussion, it has been found desirable to design the primary coils so that their maximum inductances, when considered in conjunction with their distributed capacities and the capacities of the components (including the tuning condenser) and connecting wires connected to them, are resonant at frequencies higher than the highest frequency of the respective tuning bands of the amplifier. If the resonant frequency of the primary circuit comes within a tuning-frequency band, the result may be a material reduction in the amplification and a corresponding decrease in selectivity over 100 a large part of that band. 105

The physical placement of certain of the coils produces other electrical effects which must also be considered in calculating the final performance of the complete transformer. For example, short-circuiting the low-frequency secondary coil L_4 has a pronounced effect upon the high-frequency secondary L_3 , if these two coils are placed too close together. This effect varies with the dimensions and electrical characteristics of the respective windings, but in transformers such as herein described, the too close proximity of the short-circuited coil L_4 to coil L_3 results in a pronounced increase in resistance in the coil L_3 ; thereby decreasing the amplification and the selectivity within the high-frequency band. 115

As has been noted, this figure includes a neutralizing circuit C_n , N_2 , N_1 , connected in 120 series between the grid electrode and the filament system. Since in this specific neutralization system the neutralizing coils N_1 and N_2 are electromagnetically coupled to plate coils L_1 and L_2 , the neutralizing condenser C_n be- 130

ing connected to the grid of the vacuum tube, the neutralization is effected in the plate circuit. The principle of plate-circuit neutralization is explained in Hazeltine U. S. Patent No. 1,533,858, especially as illustrated in Fig. 2 thereof, which system has been slightly modified for application to the coupling system of the present invention. Accordingly, neutralizing coils N_1 and N_2 , connected in series, are included in the coupling system of Fig. 2; N_1 being closely coupled to high-frequency primary L_1 ; and neutralizing winding N_2 being closely coupled to low-frequency primary L_2 . By properly proportioning the six different windings represented in the diagram, and by properly positioning them with respect to each other, it is thus possible to obtain entirely satisfactory neutralization over both frequency bands.

The circuit arrangement of Figure 3, insofar as the coupling system between tubes A_1 and A_2 is concerned, is similar to that of Figure 2. Here, however, an antenna system is coupled to the first radio-frequency amplifying tube A_1 (as in a radio receiver) by a coupling system fundamentally based upon the intertube coupling system hereinbefore described. The antenna circuit is designed so as to have a capacitive reactance throughout the entire operating frequency range including both bands. The secondary inductances L_{10} and L_{11} are normally identical with secondary inductances L_3 and L_4 . The primary inductances L_8 and L_9 may be identical with primary inductances L_1 and L_2 but this depends upon the antenna employed. The low-frequency band curve of Figure 4 is a fair representation of the curves of both bands of the antenna coupling system of Figure 3. A short-circuiting switch S'' for the low-frequency primary L_9 is included because the impedance of this coil may be too high in the high-frequency band to be effectively short circuited by closing the secondary switch S' . It should be noted that the switching arrangement provided in the circuit of Figure 3 may be made structurally simple and electrically efficient because all the switch arms are at ground potential.

The curves of Figure 4 illustrate specifically the approximate amplification/frequency characteristics of the antenna coupling system of Figure 3. Since the antenna circuit is resonant at a frequency between 300 and 500 kilocycles, the highest points on the two amplification curves correspond to these two operating frequencies nearest the resonant frequency of the antenna circuit. The two amplification curves are lowest at 150 and 1500 kilocycles, the two operating frequencies farthest removed from the resonant frequency of the antenna circuit, but the amplification is still sufficiently great at all frequencies within the two operating bands.

In the circuit diagram of Figure 2 the input circuit of the first amplifying tube A_1 is represented as an impedance Z , usually a tuned input circuit or an untuned antenna circuit; and the source of plate potential is shown as a battery B .

The system shown in Figure 2 may be used to couple an antenna to an amplifier, in which case the extreme terminals of L_1 and L_2 may be connected to the antenna and ground respectively, instead of to the plate electrode and filament circuit of a vacuum tube, as illustrated.

In no case in the drawings herewith are the filament heating circuits of the vacuum tubes shown completed for the reason that it is now well-known in the art that the filament or cathode of a vacuum tube may be heated by any of several methods. Likewise, the plate, or anode circuit of the second vacuum tube A_2 in each figure is shown uncompleted; but it is to be understood that such plate circuits may be completed in the same manner as the plate circuit of the tube A_1 —and so on, for as many amplifying stages as may be desired, the last stage being coupled to a detector or some other appropriate device.

Fig. 5 illustrates further modifications of Fig. 2 by which the low-frequency primary winding L_2 is purposely loaded either by means of the distributed capacity of the winding itself, or by a physical condenser connected to the winding so that the whole may be resonant at a pre-selected frequency between the two tuning-frequency bands.

The neutralizing windings shown in other figures have been omitted from Figure 5 for the purpose of simplifying the diagram. It is to be noted that such windings have no bearing on the amplification characteristics of the arrangement of this figure. (For the present discussion we may assume that the dotted connection above condenser C_5 connects the plate battery, B , to the lower terminal of inductance L_2 , i. e., that the additional resonant circuit C_5 , L_5 , is not connected.) The purpose of this modification is to provide a nearly level amplification/frequency curve over the high-frequency tuning band. This result is accomplished by arranging the separate coils of the entire transformer structure so that the low-frequency primary winding L_2 has a definite coupling with high-frequency secondary coil L_3 . Since the coil L_2 has more turns than the coil L_1 , the former may have considerable electromagnetic coupling with the secondary coil L_3 even though it is not as close to L_3 as is coil L_1 . The inductance of L_2 being much larger than that of L_1 , the coil L_2 , when considered in conjunction with its distributed capacity and any effective supplemental capacity C_2 , should be resonant at a frequency between the maximum frequency of the low-

frequency band and the minimum frequency of the high-frequency band, such as 450 kilocycles. Then the desired coupling conditions will be that the coupling between L_1 and L_3 predominates at the higher frequencies of the high-frequency band; and the coupling between L_2 and L_4 predominates at the lower frequencies of the high-frequency band. It is to be understood, of course, that the secondary coil L_4 is presumed to be short-circuited when the above-defined conditions obtain.

The graphical representation of the manner in which these relations vary is given in Fig. 5a which shows the amplification/frequency curves with only coil L_1 in the primary circuit; with only L_2 and C_2 ; and with both coils functioning together in the improved manner. The upper curve, which is practically a horizontal line between 500 and 1500 kilocycles (i.e., the high-frequency band) indicates that nearly constant over-all amplification is attained.

The above description of the operation of the circuit of Fig. 5 is concerned only with the high-frequency band, because, as is well known, the undesirable characteristics of amplifiers and coupling systems are usually more pronounced at the higher frequencies. If, however, it is desired that the low-frequency band shall also have a substantially level over-all amplification, the same principles may be applied. To illustrate; the primary coil L_5 and its associated condenser C_5 have been added to the figure, and for the present discussion may be considered to be together connected in the plate circuit of the amplifying tube A_1 , which is the primary circuit of the coupling system. To accomplish this connection the dotted line above condenser C_5 in the figure may be considered removed. For operation over the low-frequency band the switch S_1 is opened. The inductance of coil L_5 is made much greater than that of L_2 ; and the capacity C_5 of such value that the circuit C_5 , L_5 is resonant at a frequency lower than 150 kilocycles, such as 100 kilocycles. The coil L_5 is then so placed relative to coil L_4 that the coupling between L_5 and L_4 predominates at the lower frequencies of the low-frequency band; whereas the coupling between L_2 and L_4 predominates at the higher frequencies of the low-frequency band. Although Fig. 5a is shown to represent only the high-frequency band, it can as well be considered to represent the amplification over the low-frequency band as just described, since the typical amplification/frequency characteristics of the two bands will be practically identical if designed in accordance with the foregoing description. It is to be understood that if more than two frequency bands are included, additional circuits corresponding to C_5 , L_5 may be connected in order that the additional frequency bands may likewise present uniform amplification characteristics.

A coupling arrangement such as shown in Fig. 5 is especially useful when employed to couple tubes of the four-element or shielded-grip type. In such event, the circuit constants require certain modification depending upon the internal impedance of the tubes employed.

A successful physical embodiment of a coupling transformer structure designed in accordance with this invention is illustrated in Fig. 1 which is a cross-sectional view. Reference to the figure will disclose that the device includes an insulating tube 1 upon which are wound and supported the various windings already described. The tube 1 has an outside diameter of $1\frac{1}{4}$ inches and a length of $3\frac{1}{2}$ inches. In this structure, the high-frequency secondary winding L_3 is wound in a single layer over the upper portion of the insulating tube, while the comparatively fewer turns of the high-frequency neutralizing winding N_1 are placed in a single layer immediately on top of the low-potential end of the secondary winding; the high-frequency primary winding L_1 being wound in a single layer immediately over the neutralizing winding, the layers being separated by insulation such as celluloid of about .01 inch thickness. These three windings thus comprise a complete high-frequency transformer. The low frequency transformer is wound upon and supported by the same insulating tube 1 on the lower portion thereof. It also comprises three windings, but here the neutralizing winding N_2 is wound in a single layer on the insulating tube, the primary winding L_2 being wound on and immediately over the neutralizing winding, the low-frequency secondary winding L_4 of the multi-layer type being placed over the primary winding L_2 , an insulating layer being placed between the windings, as before. The spacing between the high-frequency transformer and the low-frequency transformer, along the axis of the insulating tube 1, should be such that the two transformers have a negligible magnetic influence upon each other. The exact spacing required depends largely upon the frequency bands for which the different transformers are designed, and also upon the degree of amplification per stage and upon the over-all amplification of the complete amplifier. In general, this spacing must be about $\frac{1}{4}$ inch. In the structure illustrated, the low-frequency primary and neutralizing coils L_2 , N_2 are spaced $\frac{1}{4}$ inch from the high-frequency secondary L_3 , and the low frequency secondary L_4 is spaced $\frac{1}{16}$ inch from the high-frequency secondary L_3 . Under some circumstances, such as when it is inconvenient to provide the required spacing due to other space limitations in the apparatus, or when the chosen frequency bands require it, it is necessary to electromagnetically shield or screen the separate transform-

ers one from the other by means of a metallic shield, individual to each transformer, and electrically connect to the external shield or "can" 4 which is preferably placed so as completely to surround the entire structure, except in some instances at the bottom. As illustrated in Fig. 1, this "can" may be so shaped that it is spaced about the same distance from the windings of both transformers; i. e., the contour of the can may follow in general the average contour of the transformer windings, although the electrical effect does not change much if the diameter of the can is constant. The transformer structure may be secured to the can with suitably positioned machine screws or rivets 6, and spaced therefrom by spacers 3. If required, similar screws and spacers may likewise be provided at the upper end of the transformer, although these are not shown in the drawings. To connect the various windings of the transformer permanently in their respective circuits, terminal lugs 2 may be provided around the inside of the insulating tube 1; three of such terminals being shown in the figure. In order that the entire transformer structure, including the can, may be rigidly secured to a supporting panel, or the like, a flange or a series of feet, indicated in the drawings by reference character 5, is included. If more than two frequency or wavelength bands are required, additional windings (see Fig. 5) similar to those already illustrated and described may be provided, in which event the insulating tube 11 would be slightly longer than shown.

The particular transformer structure illustrated in Fig. 1, and described herein, merely as a single typical embodiment of the present invention, was designed for use in a circuit of the type illustrated in Figs. 2 and 3 and was eminently successful in a coupling system tunable over the two frequency bands already mentioned. The transformers had the following dimensions when employed with a vacuum tube having a grid-plate capacity of $4.5 \mu\text{uf}$ and mutual conductance of 1000 micro-mhos:

50 *Coupling transformers*

Self-inductance

L_1, L_2 (with L_4 short-circuited)	$58 \mu\text{h}$
N_1, N_2 (with L_4 short-circuited)	$58 \mu\text{h}$
L_1, L_2 (with L_4 not short-circuited)	$70 \mu\text{h}$
N_1, N_2 (with L_4 not short-circuited)	$70 \mu\text{h}$
L_3 (with L_4 short-circuited)	$233 \mu\text{h}$
L_3, L_4 (with L_4 not short-circuited)	$3580 \mu\text{h}$

Mutual inductance

L_1, L_3 (with L_4 short-circuited)	$21.5 \mu\text{h}$
L_1, L_2 and L_3, L_4 (with L_4 not short circuited)	$212 \mu\text{h}$

Coefficient of coupling

L_1, L_2 and N_1, N_2	90% (approximately)

Dimensions

All coils, except low-frequency secondary L_4 , wound with No. 38 (American gauge) enameled copper wire: L_3 , 132 turns; N_1 , 12 turns; L_1 , 12 turns; N_2 , 30 turns; L_2 , 30 turns; L_4 , 321 turns of double silk-covered high-frequency cable of 20 strands of No. 38 (American gauge) enameled copper wire.

70

75

Tuning condenser, C (or C')

Minimum capacity $15 \mu\text{uf}$ (approximately)

Maximum capacity $400 \mu\text{uf}$ (approximately)

80

Neutralizing condenser capacity

$C_n 4.5 \mu\text{uf}$ (approximately)

Fig. 1a and Fig. 1b show the approximate amplification characteristics of the high-frequency transformer and the low-frequency transformer, respectively, of the structure illustrated in Fig. 1.

85

I claim:

1. A radio-frequency transformer structure including an insulating form upon which are wound a plurality of sets of windings, each set of windings comprising a complete transformer operating over a substantially different frequency band.

90

2. A radio-frequency transformer structure including an insulating form upon which are wound a plurality of sets of windings, each set of windings comprising a complete transformer operating over a substantially different frequency band, and a single metallic shield effectively enclosing said structure.

95

3. A radio-frequency transformer structure including a supporting form upon which are mounted a plurality of sets of windings, each set of windings comprising a complete multi-winding transformer, the maximum radius of one of said sets of windings being greater than that of another of said sets of windings, and a metallic shield effectively enclosing said structure and radially spaced substantially the same distance from each set of windings, whereby the electrical effect of said metallic shield is substantially the same upon all of said sets of windings.

100

4. A radio-frequency transformer structure including a supporting form upon which are mounted a plurality of sets of windings, each set of windings comprising a complete multi-winding transformer operative over a substantially different frequency band, the maximum radius of the set of windings operating over the lowest frequency band being greater than that of the set of windings operative over the highest frequency band, and a metallic shield effectively enclosing said structure and radially spaced substantially the same distance from each set of windings.

105

5. A radio-frequency transformer structure comprising a set of high-frequency wind-

110

115

120

125

130

ings and a set of low-frequency windings mounted upon a common insulating form, the set of high-frequency windings including a single-layer primary winding and a single-layer secondary winding wound one over the other, the set of low-frequency windings including a multi-layer secondary winding and a single-layer primary winding wound one over the other, said sets of windings being spaced apart longitudinally along said common form.

6. A radio-frequency transformer structure comprising a set of high-frequency windings and a set of low-frequency windings supported upon a non-magnetic form, the set of high-frequency windings comprising a secondary winding, a neutralizing winding, and a primary winding supported upon said form in the order named, and a set of low-frequency windings comprising a neutralizing winding, a primary winding and a secondary winding supported upon said form in the order named.

7. A radio-frequency transformer structure comprising a set of high-frequency windings and a set of low-frequency windings supported upon a non-magnetic form, the set of high-frequency windings comprising a secondary winding, a neutralizing winding and a primary winding supported upon said form in the order named, and a set of low frequency windings comprising a neutralizing winding, a primary winding and a secondary winding supported upon said form in the order named, said sets of windings being spaced apart longitudinally along said non-magnetic form.

8. A radio-frequency transformer structure comprising a set of high-frequency windings and a set of low-frequency windings supported upon an air-core non-magnetic form, the set of high frequency windings comprising a single-layer secondary winding, a single-layer neutralizing winding, and a single-layer primary winding supported upon said form in the order named, the set of low-frequency windings comprising a single-layer neutralizing winding, a single-layer primary winding, and a multi-layer secondary winding supported upon said form in the order named.

9. A radio-frequency transformer structure comprising a set of high-frequency windings and a set of low-frequency windings supported upon an air-core non-magnetic form, the set of high-frequency windings comprising a single-layer secondary winding, a single-layer neutralizing winding and a single-layer primary winding supported upon said form in the order named, the set of low-frequency windings comprising a single-layer neutralizing winding, a single-layer primary winding and a multi-layer secondary winding supported upon said form in the order named, said sets of

windings being spaced apart longitudinally along said common form.

10. A radio-frequency transformer structure comprising a set of high-frequency windings and a set of low-frequency windings supported upon an air-core non-magnetic form, the set of high-frequency windings comprising a single-layer secondary winding, a single-layer neutralizing winding and a single-layer primary winding supported upon said form in the order named, the set of low-frequency windings comprising a single-layer neutralizing winding, a single-layer primary winding and a multi-layer secondary winding supported upon said form in the order named, said sets of windings being spaced apart longitudinally along said form, and a metallic shield secured to and effectively enclosing said structure.

11. A radio-frequency transformer structure comprising an air-core form upon which are supported a set of closely-coupled low-frequency primary and secondary windings, and a set of high-frequency windings including a high-frequency secondary winding which is coupled to said low-frequency primary and secondary windings to a less degree than that to which said low-frequency primary and secondary windings are coupled to each other.

12. A radio-frequency transformer structure including a set of closely magnetically coupled high-frequency windings and a set of closely magnetically coupled low-frequency windings spaced apart longitudinally along a non-magnetic supporting form, the two sets of windings being substantially without magnetic coupling therebetween.

In testimony whereof I affix my signature.

WILLIAM A. MACDONALD.
